UNITED STATES PATENT OFFICE.

HERBERT FROOD AND DANIEL G. HOLMES, OF CHAPEL-EN-LE-FRITH, ENGLAND.

BRAKE-BLOCK.

No. 894,946.

Specification of Letters Patent.

Patented Aug. 4, 1908.

Application filed June 9, 1906. Serial No. 320,955.

To all whom it may concern:

Be it known that we, HERBERT FROOD and DANIEL GEORGE HOLMES, both subjects of the King of Great Britain and Ireland, and both residents of Chapel-en-le-Frith, in the county of Derby, England, have invented new and useful Improvements in Brake-Blocks, of which the following is a specification.

10 These improvements relate to brake blocks for vehicle wheels.

An improved block is composed of a mixture of vegetable fibers and small pieces or fragments of metal and with a binding of 15 suitable cementitious substance. The fibrous material preferably consists of disintegrated old woven fabrics of cotton or other material; the cementitious material may be a heated mixture of resin pitch and the india rubber cement which is manufactured from waste vulcanized rubber; the metal may be punchings, chippings, and the like scrap. A mixture of the three when in its heated condition 20 is pressed into suitable blocks, the excess of cementitious material being squeezed out. The block so formed has a composite wearing surface of metal and fibrous textile material impregnated with the binding or cementing substance.

25 A block formed as described may be attached for use to a metallic foundation block, and such foundation block may be formed with metallic studs which project into the mass of fibrous material and may be 30 utilized to form part of the wearing surface.

In the accompanying drawings Figure 1 shows in section and Fig. 2 in front elevation one of our improved blocks attached to a metallic foundation block.

35 The part A (shown in dotted lines in Fig. 1) indicates the fibrous material and B indicates pieces of metal of various shapes or sizes incorporated or mixed with such fibrous material. Such metallic pieces may have 40 roughnesses or fangs for better engagement with the fibrous material.

45 C is the foundation block to which the brake block may be secured in any suitable manner, as, for example by being pressed into dovetailed grooves or recesses or by 50 means of screws such as D which pass through the plate C and engage with the fibrous material.

In a convenient form of brake block the 55 metal forms about one third of the total

wearing surface, although it may be more or less according to the use to which the block is to be put. Of the remainder of the block the greatest portion is disintegrated fibrous material, only enough cementitious material 60 being used to impregnate the fibers and bind them firmly together.

For use upon the rims of wheels which come in contact with the ground or with rails small chilled iron studs or equivalents may 65 usefully be employed. For use upon drums or wheels which do not come into contact with the road or with rails soft cast iron may be employed.

We are aware that it has been proposed to 70 make use of a composition consisting essentially of iron in a fine state of division, mixed with small quantities of cement and fiber, but our brake surface is distinguished from this by having only about a third of its surface formed of metal in pieces of substantial 75 size with just enough cement to bind them together.

It is to be noted that the metallic pieces or bodies which are employed in the brake shoe 80 of the present invention are of considerable size, as distinguished from small iron filings or particles which have hitherto been used.

This characteristic gives an important advantage in applicants' brake shoe over those 85 of this class previously used, and which consists in the fact that the brake shoe cannot have its particles torn out bodily from its surface and spread around the track and in the atmosphere, causing short circuits and 90 other injurious results. The bodies or particles which applicants employ are of such size that no frictional force could be exerted, under ordinary circumstances, sufficient to dislodge them from the mass in which they 95 are embedded. But, even more important than this, is the fact that they are of such a size that they will fall to the ground at once, by gravity, in case they should be dislodged.

In no case will the particles or bodies which 100 form the substance of applicants' brake shoe stick or adhere to the tracks etc. of the roadway, or float in the atmosphere in the form of a dust after they have been dislodged.

It may be stated as characteristic of the 105 bodies or particles which applicants employ, that they are too large and too heavy to adhere to any object in the form of a dust or to float in the atmosphere in the form of a dust.

What we do claim as our invention and desire to secure by Letters Patent is:—

A composite brake shoe comprising fibrous vegetable material mixed with metallic pieces of substantial size and bound together by a suitable cementitious material, said pieces being all of a size too large and heavy to adhere to any solid object or to float in the atmosphere in the form of a dust.

In testimony whereof we have signed our names to this specification in the presence of two subscribing witnesses.

HERBERT FROOD.
D. G. HOLMES.
